IMPROVED COUNTERSINK BIT.

HENRY C. LEWIS, OF ESSEX, CONNECTICUT.

Letters Patent No. 60,207, dated December 4, 1866.

SPECIFICATION.

TO ALL WHOM IT MAY CONCERN:

Be it known that I, HENRY C. LEWIS, of Essex, in the county of Middlesex, and State of Connecticut, have invented a new Improvement in Countersink Bit; and I do hereby declare the following, when taken in connection with the accompanying drawings, and the letters of reference marked thereon, to be a full, clear, and exact description of the same, and which said drawings constitute part of this specification, and represent, in—

Figure 1, a front side view.

Figure 2, a back side view.

Figure 3, a section crossing $x x$; and in

Figure 4, a vertical central section.

My invention consists in combining a countersink with a bit so that when the hole of the screw to be inserted is bored to the requisite depth the same instrument will countersink for the head, and positively central with the hole itself. In boring for screws, the common practice is to withdraw the boring instrument and employ a separate and independent instrument to countersink for the head of the screw, and unless extraordinary care is used in thus countersinking, the countersink is not central with the hole. This extraordinary care required, together with the inconvenience of changing the instrument, induces the workman to drive the screw without countersinking, forcing the wood away as the head penetrates, generally tearing and disfiguring the wood. By my invention these difficulties are entirely overcome; and that others may be enabled to construct and use my improvement, I will proceed to describe the same as illustrated in the accompanying drawings.

A is the bit; B the shank, terminating in any convenient form for insertion into the brace. At the proper distance from the point of the bit—that is to say, according to the size of the screw for which the hole is bored—I form an enlargement, C, its under surface being that of an inverted half cone and corresponding to the under surface of the head of the screw; this enlarged portion is made concave upon one surface, as seen in figs. 1, 3, and 4, and so as to form a sharp cutting edge at a , (see fig. 3,) similar to the cutting edge upon the bit, thus using the proper-sized bit for the screw to be driven. The hole and countersink are made in the most perfect manner, and this construction is much cheaper than the ordinary countersink.

Having thus fully described my invention, what I claim as new and useful, and desire to secure by Letters Patent, is—

A countersink bit constructed in the manner herein described, and so as to operate as and for the purpose specified.

HENRY C. LEWIS.
